Atty.

UNITED STATES PATENT OFFICE.

HARRY T. ANDERSON, OF BUTLER, PENNSYLVANIA, ASSIGNOR OF ONE-HALF TO
SOREN HANSSON, OF BUTLER, PENNSYLVANIA.

CONNECTING BAR.

Application filed February 28, 1922. Serial No. 539,829.

To all whom it may concern:

Be it known that I, HARRY T. ANDERSON, a citizen of the United States, and resident of Butler, in the county of Butler and State 5 of Pennsylvania, have invented a new and useful Improvement in Connecting Bars; and I do hereby declare the following to be a full, clear, and exact description thereof.

My invention relates to connecting bars, 10 and more especially to such as are used for connecting the brake-levers of railway trucks, push-rods for brake-cylinders or other purposes.

The object of my invention is to provide a 15 bar or strut which is so reinforced as to provide a light but very rigid and durable bar capable of resisting the bending and compressive strains to which such bars are subjected when in use.

20 In the accompanying drawing Fig. 1 is a side view broken away of my improved connecting bar; Fig. 2 is a plan view of same; Fig. 3 is a section on the line 3—3, of Fig. 1; Fig. 4 is an enlarged section on the line 4—4, 25 Fig. 2; Fig. 5 is an end view, one-half of one of the clevis members being shown in section; and Figs. 6, 7 and 8 are cross sections of modified forms of my invention.

The body portion 2 of my improved connecting bar is preferably made of steel, and for convenience of manufacture is formed 30 from an ordinary rolled beam of an "H" or "I" section. The beam from which my improved connecting bar is made is illustrated 35 in dotted lines, Fig. 4. Such a beam, by a forging or pressing operation in suitable dies, is brought to the cross section indicated in sectional lines, Fig. 4, the flanges of the beam having been curved to form the substantially semi-circular portions 3 and 4 40 with the intervening longitudinally extending spaces or slots 5. The edges of said semi-circular portions may meet, however, if desired. The web 6 of the beam connects these 45 semi-circular portions 3 and 4 extending longitudinally and centrally of the bar, and acting as a brace or connection between said semi-circular portions, and providing a very rigid and durable construction as against 50 bending and compression strains.

The end-portions of the bar are forged to form the clevis members 7, the web-portion of the beam being removed so as to present the slots 8 for the passage of the brake-lever or other part. Simultaneously with the forming of the clevis members 7, or subsequently thereto, the bolt or pin-holes 9 are formed, there being sufficient metal in the flanges of the beam to provide the necessary pads or reinforcements 10 around the bolt-holes, while extra material is also available in web-portion. 60

The web-portion 6 of the beam, as stated above, is cut away to permit of the formation of the clevis-members 7, but said web 65 extends up close to the first bolt or pin-hole in the clevis-members, as clearly indicated in Figs. 2 and 3, which adds strength to the construction, and at the same time allows ample clearance for the movement of the 70 levers contained within the slots 8 of the clevis-members.

It is apparent that the cross-section of my improved connecting bar may vary, and in 75 Figs. 6, 7 and 8 I have shown various modifications, all of said modifications, however, containing the main feature of my invention, namely, the longitudinally extending web connecting the outside portions which are formed by the flanges of the beam, and 80 which may be of many different shapes.

What I claim is:

1. A connecting bar comprising a body portion formed of a beam with flanges and a connecting web-member, the upper and 85 lower flanges at one side of said web-member being turned inwardly, and clevis members formed at the ends of said body from the flanges of said beam, said web member being removed at said clevis members. 90

2. A connecting-bar comprising a body member with inwardly extending portions, a web-member extending longitudinally and centrally of said body, and clevis-members formed at the ends of said body, said web- 95 member being removed at said clevis-members.

3. A connecting-bar comprising a body member having oppositely disposed semi-circular portions approaching each other, a 100

web-member extending longitudinally and centrally of said body-member, clevis-members formed at the ends of said body-member, said web-member being removed at said 5 clevis-members.

4. A connecting bar comprising a body-portion formed of a beam with flanges and a central connecting web, the flanges being bent inwardly toward each other, clevis

members formed at the ends of said body 10 from the flanges of said beam, the web-member being removed at said clevis-members.

In testimony whereof, I, the said HARRY T. ANDERSON, have hereunto set my hand.

HARRY T. ANDERSON.

Witnesses:

HARRY M. HAYS,
FLOYD E. DAVIS.
